UNITED STATES PATENT OFFICE

2,512,183

VENDING MACHINE

James E. Stewart, Rye, N. Y., assignor, by mesne assignments, to Cleveland-Detroit Corporation, a corporation of Delaware

Application September 11, 1945, Serial No. 615,543

17 Claims. (Cl. 312—46)

1

This invention relates to improvements in vending machines and is directed more particularly to the provision of vending machines in which a plurality of circular shelves or supports are rotatably carried on a central vertical shaft and the articles to be vended are positioned on these shelves. The spacing apart of the shelves may depend on the height of the articles. Means is provided above each shelf for guiding the articles along several circular paths with connecting or cross-over paths extending from each inner circular path to the next outer path. Associated with each shelf is a vertically extending article delivery rotor which may be provided with an article receiving cavity and, if desired, an article display cavity.

Each article delivery rotor is provided with ratchet means making it impossible for the operator to turn it back after it has been moved forward several degrees, and the ratchet also prevents the rotor from turning back if its handle is released by the operator. Now when the article is removed from the article cavity in the rotor, the ratchet is released by the article itself and the rotor returns to its normal position under the urge of spring means.

The shelves are free on the vertical shaft which support them, and means is provided between each delivery rotor and its shelf for advancing the shelf as the rotor is returning to its normal position after the operator removes an article from the delivery rotor.

One object of the invention is the provision in a vending machine of a freely rotatable article supporting shelf carried on frictionless bearings on a central vertical shaft, said shelf being adapted to be advanced by article delivery means as a result of the action of a purchaser in obtaining the article purchased.

Another object of the invention is the provision in a vending machine carrying a plurality of circular shelves rotatably therein, of guiding means for the articles adapted to guide them along several concentric paths, each joined to the next outer one by a cross-over path, thereby permitting the shelf to be moved with a minimum of frictional retardation by the articles.

A further object of the invention is the provision in a vending machine employing a plurality of circular shelves, of article delivery means at the level of each shelf for vending articles therefrom, and means connected to each article delivery means and adapted to engage and advance the shelf associated therewith a predetermined distance during at least a portion of the movement of the article delivery means while a vending operation is effected.

Yet another object of the invention is the provision in a vending machine employing a plurality of circular shelves freely rotative on a central vertical shaft therein, of a vertical cylin-

drical article delivery means having an article cavity formed therein, said article delivery means being keyed to a second vertical shaft and spring means in the base of said machine and connected to said second shaft for causing said article delivery means to return to its normal position after having been moved to an article delivery position and the article removed therefrom, said spring means being also adapted, via said article delivery means, to power the advancing of the circular shelf as said delivery means is returning to its normal position.

A further object of the invention is the provision, in a vending machine, of a circular shelf frictionless supported on a central vertical shaft by frictionless radial and thrust bearings, said shelf having a series of perforations circumferentially disposed adjacent to its outer perimeter, a pivoted arm carried on said shaft subjacent to said shelf and having a portion extending upwardly to clear the outer perimeter of the shelf and overlying said perforations, ratchet means carried on the portion overlying the perforations, and means for moving said arm back and forth through a predetermined arc, said ratchet means being adapted to engage said perforations and advance said shelf when said arm is moved in only one of said directions.

Another object of the invention is the provision, in a vending machine, of an article delivery rotor having an article cavity therein, a member engaged by an article in said cavity, an indicator flag operatively connected to said member and visible outside said machine when said rotor is in its normal position and not engaged by an article, thereby indicating that the supply of articles is exhausted.

Other objects and advantages of the invention will be apparent to those skilled in the art after a study of the following specification and the accompanying drawings.

By way of example, the invention will be described in connection with a machine for vending bottles containing milk, fruit juices, ades, or carbonated beverages, but it will be understood that the inventive features may be applied to machines for vending many other types and kinds of articles.

Referring now to the drawings which, as pointed out above, are merely given by way of example to illustrate the invention.

Figure 1 is a front elevation of a vending machine embodying the invention;

Figure 2 is a sectional elevation showing certain details of the machine shown in Figure 1, taken on line 2—2 of Figure 7 with the middle portion omitted;

Figure 3 is an enlarged fragmentary elevation partly in section showing a portion of one of the rotary shelves, the relation of the guiding chan-

nels thereto, and the relation between the shelf and its article delivery rotor;

Figure 4 is an elevation, partly in section, showing a rotary shelf, the guiding channels, articles on said shelf, and disposed in the guiding channels, and a member for advancing said articles along the guiding channels toward the article delivery rotor;

Figure 5 is an elevation of the advancing member shown in Figure 4;

Figure 6 is a fragmentary plan view of the article advancing member shown in Figures 4 and 5;

Figure 7 is a plan view, partly in section, taken along the line 7—7 of Figure 1;

Figure 8 is an enlarged fragmentary view of a portion of Figure 7, showing details of the article delivery rotor and the means for advancing the rotary shelf;

Figure 9 is a sectional elevation taken along the line 9—9 of Figure 8, showing details of the ratchet means for advancing the rotary shelf;

Figure 10 is an end elevation of the ratchet means as seen along the line 10—10 of Figure 8;

Figure 11 is a view similar to Figure 8, showing the delivery rotor in the article delivery position and the ratchet advanced on the rotary shelf ready to advance it in a counterclockwise direction as the delivery rotor is returned to its normal position;

Figure 12 is an elevation, partially in section, of the lowermost article delivery rotor, the bottom of the refrigerated portion of the cabinet, and a portion of the lower compartment of the cabinet with the telescoped shafts of the delivery rotors extending into said lower compartment and further showing one method of mounting the common delivery rotor springs therein;

Figure 13 is a view of the bottom ends of the telescoped shafts and the springs associated therewith;

Figure 14 is an elevation, similar to Figure 12, except that the rotor is partially broken away to show mechanism in the interior thereof;

Figure 15 is an elevation taken along the line 15—15 of Figure 14;

Figure 16 is a front elevation of an article delivery rotor;

Figure 17 is a plan view of the rotor shown in Figure 16;

Figure 18 is a view of the bottom of the rotor as seen along the line 18—18 of Figure 16;

Figure 19 is a sectional elevation taken along the lines 19—19 of Figure 17;

Figure 20 is a view of the delivery rotor in its normal position and showing a bottle entering the article cavity;

Figure 21 is a view similar to Figure 20, except that the rotor has been rotated to a position where the purchaser may remove the bottle from the article cavity;

Figure 22 is a view, similar to Figure 20, except that it shows details of the mechanism on the bottom of the delivery rotor and elements cooperating therewith;

Figure 23 is a sectional elevation taken on the lines 23—23 of Figure 22;

Figure 24 is a fragmentary view showing a rotor locking member in elevation;

Figure 25 is a sectional elevation showing the pawl member employed in the article delivery rotor;

Figure 26 is an exploded view of the several elements employed in forming sections of the rotor shaft.

Figure 27 is a plan view of the rotor return dog;

Figure 28 is a plan view of the ratchet dog;

Figure 29 is a front fragmentary view of a lock-out device for preventing the operation of more than one rotor at one time, and

Figure 30 is a side elevation of the device shown in Figure 29.

Referring first to Figure 1, the cabinet, generally designated by the numeral 30, includes a main portion 31, a top portion 32, and a bottom portion 33, and these three portions comprise a unitary insulated and refrigerated structure, supported on an uninsulated base 34.

The cabinet has a door 35 through which the cabinet may be resupplied with articles, and the door 35 may be provided with a suitable lock 36. Spaced vertical panels 37 and 38 are provided on the cabinet. The panel 37 has a coin slot 39 near its upper end and intermediate the ends is a coin return cup 40, and a lock 41. Behind the panel 37 is the usual coin tester and a coin mechanism, not shown. The panel 38 is substantially identical and it has a coin slot 42, a coin return cup 43 and a lock 44. Behind this panel is the usual coin tester and a coin mechanism, not shown. The two coin mechanisms have equal control over all the merchandise delivery means in accordance with my co-pending application, Serial No. 537,989, filed May 30, 1944; so that, in the event either coin mechanism gets out of order, merchandise may be purchased via the other one. The manner in which either coin mechanism may release an article delivery rotor will hereinafter be described.

The cabinet top portion 32 may be curved, as shown in Figure 2, and domed in the center, the dome being 45 and the curved portion designated as 46, and consisting of an inner plate and an outer plate with insulation therebetween, said plates being secured to the annular wooden ring or breaker strip 47. Within the center of the top, below the dome 45, is formed a cavity 48. A motor 49 mounted in the cavity carries a circulating fan 50 and a switch casing 50a therefor, so that the fan may circulate the air within the cabinet. The main portion 31 may consist of inner and outer tubular walls with insulation therebetween; the tubular walls are joined together by an annular ring 51 at the top end and by an annular ring 52 at the bottom. These rings may be formed of hardwood or any other suitable material. Where the opening for the door 35 is formed in the walls of the cabinet, suitable closure trims 53 are provided to bound or frame the opening. The door 35 has outer and inner walls with insulation therebetween and the edges of the door are trimmed or finished off with a closure trim frame 54, the beveled surfaces are parallel to the adjacent edges of the trim 53 (when the door is closed) and sealing is effected by means of the gasket strip 55.

The bottom portion 33 of the insulated compartment has a flat bottom plate 56 having an annular portion 57 deformed as shown in Figure 2, to accommodate a wooden ring 58 and the annular stepped upper edge of the base wall 34. Spaced apart from the bottom plate 56 is an annular plate 59 which has a central flat portion 59a. Between the extremity of the plate 59 and the annular portion 57 is an annular wooden ring 60. Between the annular ring 60 and the annular ring 52 at the bottom of the main portion 31, is an annular gasket 61. Bolts, such as the bolt 62, extend through the rings 58, 60, and 52 and

engage nut members such as 63 secured to the ring 52, for securing the bottom portion 33 to the bottom of the main portion 31.

An annular gasket ring 64 is provided between the rings 47 (in the top portion 32) and 51 (in the upper end of the main portion 31) and bolts, such as the bolt 65, extend through the rings 47 and 51 to engage nut members, such as the member 66, secured to the ring 51.

An angle support 67 is secured to the interior wall of the main portion near the bottom thereof and supports the lower end of an arcuate evaporator or low side grid 68. Pipes 69 and 70 respectively are connected to a refrigerating high side unit (not shown) in the base 34. The pipe 69 may be the liquid line and the pipe 70 may be the return or suction line. The method of supporting the upper end of the grid 68 will presently be described.

A vertical shaft 71 is supported in the cabinet and extends from the flat portion 59a of the bottom 33 to a socket formed in the fan housing 50a. This shaft is fixed and forms the support for the several round shelves to be presently described. The fan housing 50a is secured to the top portion by a plurality of screws such as those shown at 72, and the shaft 71 may have a hollow interior 73.

A shouldered sleeve member 74 is provided with an annular flange 75, and the interior bore of the sleeve member may clear the shaft 71. An annular, cupped bracket 76 is secured to the plate portion 59a, and its cup supports a radial-thrust ball bearing 77, the interior of which accommodates the lower end of the sleeve 74. The lower shoulder of the sleeve abuts the upper face of the inner race of the ball bearing. The upper shoulder of the sleeve 74 engages the inner race of a second radial-thrust ball bearing 78. The outer race of this bearing fits in the bore 79 of a stepped member 80. The member 80 has a portion fitting the shaft 71 and secured thereto by means of a set screw 81. From the above it will be seen that the sleeve 74 is freely supported on spaced ball bearings 77 and 78.

Secured to the flange 75 by means of rivets 83 is an annular shelf 82, which is substantially stiffened by webs or ribs 84. Leaving Figure 2 and referring to Figure 7, a plan view of the shelf 82 shows four such ribs or webs 84 and they are preferably radial. The shelf also has a series of perforations 86 adjacent to the periphery thereof which are employed for advancing the shelf in a manner to be presently described, and the shelf carries a radial slot 85 which cooperates with a merchandise pusher which will also be described hereinafter. Referring back to Figure 2 it will be noted that the sleeve 74 and the ball bearings 77 and 78 support the bottom shelf. The arrangement of the spaced ball bearings supporting the other shelves is slightly different.

Referring to Figure 3, the bearing supports for all of the other article shelves 82 except the bottom 82a, described above, are identical, therefore the description of only one of them need be given. The annular shelf 82 has a central hole therein which fits over a boss 87 formed on a hub 88, and this shelf is secured to a flange 89, formed on said hub, by means of rivets 91. The hub has steps formed thereon to accommodate the inner races of spaced ball bearings 92 and 93.

A casting 95 has a cup portion 96 which is stepped to accommodate the outer races of the ball bearings 92 and 93. The upper end of the 75

cup portion has a radial flange 94 formed integral therewith, the purpose of which will be presently described. Formed integral with the cup portion 96 is a hub portion 97 with oppositely disposed lugs 98, 99. This hub has a bore therein which is concentric with the stepped interior bore of the cup portion and which forms a working fit on the shaft 71. The lugs 98 and the lower end of the boss 87 are slit. Clearance holes to clear the bolts 99 are formed in the lugs to one side of the slits, and tapped holes are formed in the lugs on the other side of the slit, so that the screws may be tightened to clamp the casting on the shaft 71 in a position where the shelf 82 is exactly the right distance from its upper and/or lower neighbors.

Obviously since the casting 95 is clamped on to the stationary shaft 71 it is also stationary. The flange 94 on this casting has secured thereto by means of rivets 101, a supporting plate 100 for concentric guides for the articles. Turning now to Figure 4 for a sectional elevation of these guides and to Figure 7 for a plan view in which the plate 100 per se is omitted so that the guides 20 may be clearly seen, the inner guide 102 is concentric with the axis of the shaft 71 and is circular throughout about 300° and a straight portion 102a extends outwardly to join the beginning of a second circular guide 103 at the point 104. The circular guide 103 is concentric with the circular guide 102 and has a straight portion 103a which is parallel to the portion 102a and which joins a third circular guide 105 at the point 106. The guide 105 is also concentric with 25 the shaft 71 and the other guides, and it has a straight portion 105a, parallel to the portion 103a and which joins a fourth circular guide 108 at the point 109.

The circular guide 108 is concentric with the 30 others and adjacent to the delivery rotor (to be presently described) it is curved outwardly, the curve being designated as 110.

An angular extension is mounted on the guide 105 and is so positioned thereon that its apex 45 112 is adjacent to the delivery rotor for a purpose to be more clearly pointed out. Lugs 107 formed on these guides extend into corresponding holes in the plate 100 for facilitating the assembly thereto of the plate-guide unit by bending them down flat and brazing them down.

The guides may all have beads 113 formed 50 therein near the lower ends thereof, and similar beads 114 spaced apart therefrom, so that their apexes contact the articles and allow them to be moved with a minimum of friction.

Referring again to Figure 2, it will be noted that the top plate-guide unit in the machine is secured to an annular flange 115 by means of rivets 60 116. Integral with the flange 115 is a hub 117 having oppositely disposed lugs 118 carrying clamping bolts 119. The lugs may be split and formed similar to those on the castings 95 described hereinbefore so that the hub 117 may be firmly clamped on the shaft 71. The upper end of the cooling grid 68 may carry straps 120 which may be supported on the top plate 100.

Referring again to Figures 3 and 4, the hub 122 of a shelf advancing arm 121 has a tubular flange 123 formed integral therewith and this flange embraces and forms a working fit on the periphery of the flange 90 (which carries the circular shelf 82). The shelf advancing arm extends rearwardly at an angle, therefore its length and shape can best be seen in Fig. 4. It extends horizontally 70 adjacent to the plate 100 toward the periphery.

It has a vertical portion 124 and a horizontal portion 125 adjacent to the shelf 82 extending beyond the periphery thereof. The portion 125 has a clearance hole 126 formed therein, through which pawls, to be presently described, may project.

Mounted on the end of the portion 125 is an arcuate spacer 127 (Figures 4, 8, 9, and 10) which parallels the edge of the shelf 82 with a clearance space 128 therebetween. Bolted to the portion 125 and the spacer 127 is the horizontal leg 129 of an L shaped bracket 130. The vertical leg 131 of the bracket overhangs the edge of the shelf 82. Secured to the leg 131, by means of rivets 132, is a body 133 having slides 134 and 135 formed therein for plungers 136 and 137 respectively. A thin plate 138 therebetween separates the plungers. The plunger 136 has a hole therein for a spring 140 and the plunger 137 likewise has a hole therein for a spring 139. A top plate 141 is secured to a web 142 projecting from the body 133 by means of bolts extending through the holes 143 formed in said web. The springs 139 and 140 bear against the top plate 141 and urge the plungers downwardly. The plunger 136 has a triangular tip 144 and the plunger 137 has a triangular tip 145, and since the plungers are rectangular, the tips always face the same direction, and as the shelf advancing arm 121 is moved (in a manner to be presently described) to the right as viewed in Figure 8, the plunger tips ratchet over the perforations 86 formed in the shelf 82. As the arm 121 is moved to the left, the tips on the plungers engage the perforations 86 and move the shelf 82 in the direction of the arrow.

A bushing 146 extends through the portion 125, the spacer 127 and the leg 129 and forms a bearing for the shank of a headed pin 147, Figures 8 and 10. A connecting rod 148 has one end connected to the pin 147 by means of a bearing hole therein which is journaled on the pin 147. The other end of the connecting rod 148 is connected to a member in the article delivery rotor as will presently be described.

Referring again to Figure 7, it will be noted that the articles to be vended are shown, by way of example, as bottles 149. Obviously the machine can be used to vend many other kinds of articles, and these articles may be refrigerated, or non-refrigerated. An article pusher generally designated by the numeral 150 may move radially in a slot 85. It "follows up" the last bottle or article in the series in a manner to be presently described.

The article pusher 150 is shown in a sectional elevation in Figure 4, in full elevation in Figure 5, and in plan in Figure 6, Figures 5 and 6 being enlarged. Forming a working fit in the slot 85 is a spacer sleeve 151, the lower end of which abuts a spring base plate 152 below the shelf 82, and the upper end of which abuts a similar base plate 153; a spacer sleeve 154 has its lower end in contact with the base plate 153, and its upper end abuts a disc 155 which may be substantially the same diameter as the largest diameter of the articles. A second disc 156 may abut the disc 155 and may be of the same diameter. A spacer sleeve 157 has its lower end abutting the disc 156 and its upper end in contact with a disc 158 which may be the same diameter as that of the discs 155 and 156. A threaded rod 159 extends through holes in the array of spacer sleeves, discs, and base plates, and nuts 160 and 162 with washers 161 and 163 respectively associated therewith

serve to clamp the array together. A spacer sleeve 164 is positioned between the base plates 152 and 153. A threaded rod 165 extends through aligned holes in the sleeve and the two plates and the array is clamped together by means of nuts 166 and 167, and lock washers. Both the spacer sleeves 151 and 164 lie within the slot 85 and form a working fit therein. The base plate 152 may carry rollers 168 which engage the lower surface of the shelf 82, and likewise the plate 153 may carry rollers 169 which engage the upper surface of the shelf 82.

Referring to Figure 7, the operation of the pusher 150 is as follows:

The perforations 86 in the shelf 82 have been described, and the plungers 136 and 137 have been described as carrying tips 144 and 145 respectively which, when moved to the right, ratchet over the perforations 86, and when moved to the left, engage perforations 86 and move the shelf 82 in the same direction. The arm 148 has been described as connected to the extension 125 which supports the plunger holder. The other end of the arm 148 is pivotally connected to an arm 170 which is associated with and moves with the article delivery rotor 172 toward the right (as seen in Figure 7) when said rotor is turned to the delivery position, and toward the left when the rotor is returning to its normal position. The details of the numerous novel features of the article delivery rotor will presently be described in detail. For an understanding of the operation of the article pusher, it is sufficient to understand that the article delivery rotor has a cavity 171 for receiving the outermost or end article 149 of the series positioned on the shelf 82 and extending into and guided by the stationary circular guides 102, 103, 105, 108, and the intermediate cross-over guides.

As shown in Figure 7, the bottle 149a is in the cavity 171. When the rotor 172 is turned clockwise to bring the cavity 171 outside the cabinet so that it may be lifted out, the plungers 136 and 137 ratchet over the perforations 86, as said plungers are moved counter-clockwise (due to the linkages 170, 148). After the article 149a is lifted out, the rotor returns to its normal position (moving in a counter-clockwise direction) and at least one of the plungers 136 and 137 engages a perforation 86 and the shelf 82 is advanced in a clockwise direction, causing the article in the position 149b to enter the cavity. Since the articles 149c around to 149e lie between the concentric stationary guides 105 and 108, the articles 149g to 149m lie between concentric stationary guides 103 and 105 and the articles 149p to 149y lie between concentric stationary guides 102 and 103, they do not impose any frictional load, as would be the case if the stationary guide were spiral as shown in my co-pending application Serial No. 490,995, filed June 16, 1943, which matured as Patent No. 2,423,265, July 11, 1947. The only extra frictional load is imposed where the articles move from one circle to the next adjacent outer one. For example, articles in the positions 149n move laterally from the circular path between guides 102 and 103 to the circular path between guides 103 and 105; and articles in the positions 149f and 149g are moved laterally to pass from the circular path between the guides 103 and 105 to the circular path between the guides 105 and 108. Also the article moving from the position 149c to the position 149b is moved laterally by the deflector 111. Since a minimum number of articles is moved

laterally, the force necessary to move the shelf 82 is kept at a minimum.

As the article in the position 149b enters the cavity 171, all of the other articles move up one position. Now since the article pusher 150 is "backing up" the last article in the series (149y) and since it is positioned in the slot 85 in the shelf, the movement of the shelf keeps advancing the pusher 150 each time the shelf 82 is advanced, and the pusher always follows the last article. As the last article passes through the passage between guides 102a and 103a to pass from the inner circular path to the next outer one, the pusher 150 follows it up as it can also move radially in its slot 85. This is also the case when the last article is passing through the passage between guides 103a and 105a to enter the outer circular path, the pusher follows it up and enters the outer circular path also. When re-loading the shelf, the service man places articles on the shelf advancing the pusher 150 backwards or retrograde so that the articles and the pusher assume the positions shown in Figure 7.

Although any type of coin mechanism may be used in the machine herein shown and described, I prefer to employ dual coin mechanism in accordance with my co-pending application, Serial No. 537,989, filed May 30, 1944. One coin mechanism (not shown), may be positioned in a cavity 173, Figure 7, in the door 37 and another in a cavity 174, in the door 38. The coin mechanism in the cavity 173 may control a bar 208 and the other may control a bar 207. The manner in which these bars function, and elements associated therewith, will be presently described in detail.

It will be understood that the shelves and their cooperative stationary guides are identical and that as many of them may be employed as desired.

Referring now to Figure 16, the article delivery rotor 172 is shown in elevation, and all of them are generally alike except that the heights may vary in accordance with the spacing of the shelves with which they cooperate. These rotors will presently be described in detail. It will, however, be noted that secured to the bottom plate 177 of the delivery rotor is a pad or support 178. Mounted on the support 178, as may best be seen in Figures 22 and 23, is a bearing stud 179 having a head 180. Journaled on the stud 179 is a bushing 181 carrying a lug 182, from which a pin 183 projects. The bushing 181 also carries a shaped lug 184 and a tail piece 185.

The support 178 also carries a stud 186 against which an arm 187 of a rotor return dog 188 may bear. The rotor return dog has a tongue or key 189 which extends through a clearance slot 190 formed in an outer tubular shaft 191 and engages a slot 237 formed in a shaft 193 which is telescoped in the shaft 191. Within the base of the machine is carried spring means associated with the shaft 193 for urging the rotor 172 toward its normal position. This spring means will presently be described. Spaced apart from the bottom of the rotor, by the thickness of a flange 194, carried on a bushing 195, is a stationary plate 196.

Formed in the plate 196 is an arcuate slot 197 which widens out near one end, the widened portion being designated by the numeral 199. A flat angular surface 198 joins the surfaces of the first and the second described portions and against which the pin 183 cams in a manner to be presently described.

The dog 188, opposite the arm 187, is cut away to form flat surfaces 200 and 201, at right angles to one another. A roller 202 normally bears against these surfaces and locks the dog against movement. In other words, the dog is prevented from moving in one direction by the stud 186 against which the arm 187 bears, and is prevented from moving in the opposite direction by the roller 202 contacting the surface 200.

5 The roller 202, which forms a part of the coin controlled lock 235, is journaled on a shouldered stud 203 rigidly secured to a bar 204. This bar has spaced holes into which are fitted the larger diameters of shouldered rollers 205 and 206.

10 The larger diameter of the roller 205 also fits into the reduced end of a rod 207 which may be moved by a coin control mechanism (not shown). Likewise the larger diameter of the roller 206 fits into the reduced end of a rod 208 which may be moved by a second coin control mechanism (not shown). I contemplate using dual coin control mechanisms so that if one of them gets out of order, articles may still be freely purchased via the other coin control mechanism, as disclosed in my co-pending application Serial No. 537,989, filed May 30, 1944.

The coin controlled lock 235 which may be unlocked by either coin control includes a bracket 209, offset as shown in Figure 23, a flat bar 210 and a spacer bar 211 which are all permanently secured to a stationary lower plate 212, for example by means of rivets 213. The bracket 209 and the bar 210 have aligned arcuate slots 214 formed therein for the reduced ends of the roller 205, and aligned arcuate slots 215 for the reduced ends of the roller 206. Normally the rods 207 and 208 are held against movement by their associated coin control mechanisms and the roller 202 locks the dog 188 against movement.

15 40 If the rod 207 is released, by the insertion of the proper coins in its coin control mechanism, the rotor 172 may be rotated to the left, thereby causing the stud 186 (mounted in the plate 178 carried on the bottom plate 177 of the rotor) to move to the left, as seen in Figure 22. The stud 186 bears against the arm 187 and causes the said arm to move therewith, thereby effecting the movement of the dog 188 in a clockwise direction as viewed in Figure 22. The movement of the surface 200 against the roller 202 causes the bar 204 to move in a counter-clockwise direction about the roller 206 as a fulcrum (since the rod 208 is held stationary by its associated coin control mechanism) and the roller 205 moves sufficiently in its arcuate slots 214 for the roller 202 to swing out. The dog 188 has a tongue portion 189 which acts as a key and engages a slot 237 for the purpose in the inner shaft 193, so that, as the dog 188 is rotated by the rotor as above described, the inner shaft 193 rotates and tensions a spring (to be presently described) in the base of the machine. The purpose of the said spring is to urge the rotor back to its normal position.

9445 9450 9455 9460 94

the rotor returns to normal, the pin 183 leaves the surface 197, the tail piece 185 strikes a pin 217 carried on the stationary plate and effects the disengagement of the lug 184 from the dent 216.

Mounted on the shaft 191, and having its lower surface in contact with the upper surface of the dog 188, is a washer 217. Between the washer 217 and the lower end of the bushing 195, is a disc 218, having a flat portion 219, and a key 220 which engages one edge of the clearance slot 190 formed in the shaft 191, (see also Fig. 28). Above the disc 218, and journaled on the outer surface of the bushing 195, is a ratchet dog 221 which may be secured to the disc 218 by means of rivets 222.

The ratchet dog 221 is preferably formed integral with the arm 170, previously described as linked to the ratchet means for advancing the shelf 82. This ratchet dog may carry a plurality of ratchet teeth 223, 224, and it also has a flat portion 225 which is also engaged by the stud 186, so that as the rotor is moved as described in connection with the description of the movement of the dog 188, the ratchet dog is also moved in a clockwise direction. The ratchet teeth 223 and 224 are adapted to be engaged by a pawl tooth 226 carried by a ratchet arm 227. The ratchet arm is journaled on a stud 228 carried on the stationary plate 196. The plate also carries a cupped plunger 229 which is engaged by a spring 230 mounted in a holder 231 secured to the plate by means of rivets 232. The plunger 229 urges the ratchet arm against the dog 221. As the rotor is turned in a clockwise direction the stud 186 acting against the surface 225 of the dog 221 causes the dog to move clockwise, and the tips 144 and 145 (Figure 9), ratchet over the perforations 86 in the shelf 82 as the rod 148 moves to the right as seen in Figure 8. At the same time the pawl tooth engages the ratchet tooth 224 or the ratchet tooth 223, depending on how far the rotor is moved. Since the dog 221 has a key 220 which engages an edge of the clearance slot 190 formed in the shaft 191, the shaft 191 tensions a spring in the base of the machine, and this spring causes the shaft 191 to rotate in the opposite direction after the rotor has reached the point, in its return to normal, where the stud 186 engages the surface 233 on the ratchet arm 227, and disengages the pawl tooth 226 from the ratchet tooth 223 or 224. This allows the spring to rotate the shaft 191 and the dog 221, keyed thereto, in a counter-clockwise direction. The arm 170 then moves the tips 144 and 145 to engage perforations 86 and rotate the shelf 82 in a clockwise direction, thereby moving the next succeeding article 149 into the article cavity 171 of the rotor.

The ratios of the arms 121 and 170, and the length of the link 148 and the throw of the shelf advancing dog 221 (of which the arm 170 is a part) are such that they tend to over-drive or move the shelf more than the mere diameter of the articles, etc.

If the rod 208 is released, by the insertion of the necessary coins in its coin control mechanism (instead of the rod 207 as above described) the movement of the rotor causes the dog 188 to move in a clockwise direction and the surface 200 thereof acting against the roller 202 causes the arm 204 to move counterclockwise about the roller 205, and the roller 206 moves in the arcuate slots 215 sufficiently for the roller 202 to clear the outer diameter of the dog 188.

It will be understood that I prefer to employ only one coin released lock 235 together with its coin controlled rods 207 and 208. When used in a machine where a plurality of article shelves and a plurality of article delivery rotors are employed, the coin released lock is preferably associated with the rotor return dog 188 associated with the lowermost article delivery rotor in the series, as shown in Figure 12. The rotor return dogs associated with the other rotors in the series may be identical with the one 188 above described. They are all keyed to the inner shaft 193 and consequently, when any rotor is operated, they all move in unison, but only the one on the 5 rotor is locked to the rotor by the engagement of the shaped lug 184 with the curved notch 216, due to the cooperation of the pin 183 with the surfaces 198 and 197. Since the shaped lugs 184 on the rotors not operated are not locked in, the non-operated rotors do not move.

Now in respect to the ratchet dog 221, and referring to Figure 28, the keys 220 connected to all of the ratchet dogs bear against the edges 236 of the clearance slots 190 in the shaft 191. Now if any rotor of the series of rotors is operated, the stud 186 of the rotor operated bears against the surface 225 of the ratchet dog 221 associated therewith and as the rotor moves its ratchet dog in a clockwise direction, the shaft 191 is also rotated in a clockwise direction due to the engagement of the key 220 with the edge 236. The non-operated rotors do not move their associated ratchet dogs 221, so the edges 236 of their clearance slots in the shaft 191 move away 15 from the keys 220 of said associated dogs. When the tooth 226 on the arm 227 engages the teeth of the ratchet dog of the operated rotor, said dog and the shaft 191 are held at rest, but are urged in the opposite direction (counter-clockwise) by 20 the spring means in the base of the machine, and when the stud 186 engages the surface 233 of the arm 227, the ratchet dog is released and the said spring means in the base of the machine rotates the shaft 191 in a counter-clockwise direction and moves the ratchet dog in the same 25 direction to turn it back to its normal position. As this occurs, the shelf associated with the operated rotor is advanced by the plunger tips 144, 145 engaging the perforations 86 in said shelf, 30 in the manner previously described, to effect the moving of the next article in the series, on said shelf, into the cavity 171 of the operated rotor.

The shaft 193 is formed of a plurality of short lengths shown in Figure 26. The upper ends of 35 all of the lengths, except the one at the top of the machine (which is plain), have slots 237 and 238 formed therein. The slot 237 has been described above as engaged by the key or tongue portion 189 of the rotor return dog 188. The slot 238 of each length is engaged by a downwardly 40 projecting tongue 239 on the lower end of each length immediately above. A plug 240 has half its length forced into the lower end of each length 193, and as these lengths are assembled, the 45 projecting portion of the plug is fitted into the upper end of its neighbor immediately below. The bottom length 193a, Figures 12 to 15, has its lower end plain and a crank arm 241 has a hub 242 fitted thereon and keyed thereto by means 50 of a pin 243. A spring 244 has one end secured to the arm 241 and the other end is secured to an eye 245 carried by a bracket 246, and has associated therewith a dash pot 247 to smooth out the action of the spring 244.

55 The shaft 191, returning to Figure 26, is also

formed of a plurality of short tubular lengths. The upper end of each length (except the top one which is plain) has a slot or notch 248 formed therein into which a tongue 249 on the lower end of its neighbor (immediately above) extends. The lower end of each length (except 191a) in addition to having a tongue 249, also has the clearance slot 190 previously described and having an edge 236 against which the key 220 of the ratchet dog 221 of an operated delivery motor bears in the manner above described.

The lengths 191 are telescoped over the lengths of shaft 193, and both are built up as the delivery rotors and their cooperative elements are assembled into the machine, starting with the bottom rotor. The bottom length 191a has its lower end plain and has secured thereto the hub 250 of a crank arm 251, a taper pin 252 functioning as a key. A spring 253 has one end connected to the arm 251 and its other end is connected through dash pot means 254 to an eye 255 on the bracket 246, so that the recoil of the spring is "slowed" so that when the ratchet dog 221 is released by the arm 227, a smooth advance of the article shelf 82 is effected.

The shaft 193a (Figure 12) carries a washer 256, in contact with the hub 242, and above the washer 256 is a disc 257 keyed to shaft 193a by means of a pin 258.

The shaft 191a carries in contact with the hub 250, a disc 259 which is keyed to the shaft 191a by a pin 260. Between the disc 259 and a frame cross member 261 is a plate 262. A stepped cup 263 has a hole therein in which the washer 256 reposes, and the interior accommodates the other parts described. The cup member 263 has a rectangular flange 264 which abuts and matches the plate 262, and this flange and the plate are secured to the frame member 261 by means of screws 265. The cup 263 is provided with an arcuate slot (not shown), permitting the arm 251 to swing through an arc of 90 degrees, and openings to gain access to the keying members 252, 258, and 260.

The article delivery rotor is hollow and generally cylindrical in form, as may be seen in Figures 16, 17 and 18. The bottom end 171 of the rotor may be seen in Figure 18. It has an open arcuate portion 266 bounded by an arcuate edge 267 and radial ends 268 and 269. This open arcuate portion forms clearance for an arcuate ratchet plate to be presently described. A notch 270 is formed therein providing clearance for a depending pawl 271. Adjacent to and partly breaking into the notch 270 is a slot 272 through which a rotor locking dog (to be presently described) extends.

The pad or support 178, which may be seen on the bottom of the rotor has been already described as carrying elements which control the rotor return dog 188, and the shelf advancing ratchet dog 221.

The bottom plate has an open portion 273 which is circular at 274 and is joined by tangential sides 171 and 276 extending to the periphery of the plate. Extending into the space above the open portion 273 is the end of a plunger 277 which will presently be described. A central hole 278 is formed in the bottom plate and it extends through a boss 279 on the upper surface of the plate and journals on the shaft 191 when the machine is assembled.

The rotor has a top plate 280 which is spaced apart from the bottom plate 171 by arcuate wall

portions to be presently described. The top plate has a central hole 281 extending through a boss 282. This does not show in Figure 17, due to the fact that the plate is broken away to show the location of other elements, but it may be seen in Figure 19. The top plate has an arcuate portion 283 larger in diameter than the rotor, and has secured thereto, by means of rivets 284, a lockout cam 285. A round hole 286 is formed in the top plate 280 with its center in vertical alignment with the center of the arc 274 formed in the bottom plate 171.

Between the top and bottom plates of the rotor are distance rods 275, 287, 288, 289, and 290 and screws 291 extending through holes in the top and bottom plates secure the plates and the rods together rigidly.

Referring now to Figures 20 and 21, the rotor includes boundary walls extending between the bottom plate 171 and the top plate 280, and the top plate 280 is removed in these figures so that these walls and the elements they enclose may be seen from above. The article cavity 171 is defined by an arcuate wall 292. This wall at and near the bottom thereof is substantially concentric with the article 149 (when the latter is positioned therein as shown in Figure 21), and a little farther up the wall tapers to the right so that the wall at its top is partially oval in outline. At the top of the rotor the wall includes an arcuate portion 293 and a second arcuate portion 295, joined by a straight portion 294. This provides a clearance surface 296 so that the customer may readily grasp the article, allowing his fingers to lie on the article in the space between it and the surface 296.

The wall 292, near the bottom thereof, has formed integral therewith a boss 297 which is bored out to form a working fit with a plunger 298 having a head 299 formed thereon. The head 299 (when no article is in the cavity 171) rests against the boss 297 under an urge to be presently described and the length of the plunger shank is such that it projects into the cavity 171 a substantial distance as shown in Figure 20, so as to be engaged by the next article entering the cavity 171 and is forced thereby to the position shown in Figure 21.

Joining the wall portion 293, via a corner boss 301, is a curved portion 300, the outer surface of which forms the outer periphery of the rotor extending in a clockwise direction to join a boss 302. Radially spaced apart from the boss 302 is a boss 304. Extending inwardly from these bosses are straight portions 308 and 309 respectively which blend with a curved portion 310 therebetween. The wall 311 of these bosses, the straight portions and the curved portion define a cavity 312 which is exposed to view when the rotor is in its normal position, and this cavity may be used for display purposes.

The bosses 302 and 304 are notched at 305 and 306 respectively to accommodate a transparent cover panel 307, which may be secured thereto by means of screws 425 passing through a metallic trimming frame 426, as may be seen in Figure 16.

The wall portion 300 (Figure 19) has a hole 427 formed therein through which a bolt 428 extends. The bolt carries a washer 317 bearing against its head 316 within a ball or handle 318 and backed up by a member or web 319 therein. The ball bears on a cupped washer or socket 429 outside the rotor. Inside the rotor is a special washer 313, and a lock washer 315 on the bolt prevents

the nut 314, which engages threads on the bolt, from becoming loose.

The boss 304 joins one end of a curved wall portion 320 which has substantially the same radius of curvature as the wall 300. The other end of the wall portion 320 joins a straight portion 321 and the straight portion in turn joins a curved portion 322, which has a radius of curvature less than the radii of the portions 300 and 320. The portion 322 joins the wall portion 295 via a corner boss 323.

A post 324 secured to the bottom plate 171 of the rotor has a portion 325 of reduced diameter forming a shoulder against which an arm 326 journaled on 325 bears (Figure 19). Spaced apart from the arm 326 is an arm 327 with a spacer sleeve 328 therebetween, and this array is secured on the portion 325 by a nut 329 with washer 330 between the nut and the arm 327. The arms are also spaced apart by a shouldered stud 331 riveted therebetween. The arm 327 has an arcuate extension 332 (Figures 20 and 21), the end 333 of which is narrowed and rounded on its extremity so that it may pass through a slot 334 formed in the wall 293 adjacent to the bossed portion 301. The lower arm 326 may also have an arcuate extension 332a like the extension 332 and lying beneath it as seen in Figures 20 and 21. A shouldered stud 331a joins the rounded ends of both extensions, and they may pass through the slot 334, as shown in Figure 21, to engage and steady the article 149 in the article cavity 171.

A spring 335 has one end connected to the stud 331 and its other end is connected to the distance rod 275. This spring urges the arms in a direction to cause the narrowed and rounded ends of said extensions to project through the slots 334 to engage and steady the article 149 in the cavity 171.

A post 336, Figure 14, on the bottom plate 171 has a portion 337 of reduced diameter upon which one end of an arm 338 is journaled. A nut 339 threadedly engages threads on the outer end of said portion and retains the arm 338 and a washer 340 on the portion 337 of the post. The free end of the arm 338 contacts the head 299, of Figures 20 and 21, of the pushrod 298 and also engages an upright portion 341 of the lock and ratchet assembly. A rectangular horizontal bar 342 has a round shank 343 formed on one end. This shank extends through a countersunk hole 344 in the lower end of the upright portion and is riveted as shown in Figure 25. The opposite end of the bar has a longitudinal hole 345 formed therein, into which the shank 346 of a pawl member 347 is reciprocally mounted.

The pawl member 347 has an L shaped head 351 the end of the horizontal portion of which forms a pawl tooth 352. The shank 346 has a cross-hole 350 formed therein, into which a pin 349 is forced. The end of this pin extends through an elongated hole 348 extending longitudinally in the bar 342, and this pin permits the pawl member to reciprocate in the hole 345 and yet prevents the pawl member from turning from its normal position.

The end of the shank 346 has a hole therein to accommodate a spring 353 which urges the pawl member to the right as seen in Figure 25.

A stamped plate 354, secured to the bottom plate 171 by screws 363, has a portion 355 bent to embrace a portion of the bar 342, as may be seen in Figures 20 and 21, and an upright ear 356, Figures 20 and 25, has a hole formed therein which is rod 357 may reciprocate. The rod is

mounted in the upright 341, and a spring 358, embracing the rod 357, contacts both the upright and the ear 356, thereby urging the bar 342, the pawl member 347 and the upright to the left as seen in Figure 25, and consequently the upright is maintained in contact with the arm 338, and this arm, in turn, is maintained in contact with the head 299 of the plunger 298.

The vertical leg of a bracket 359 is secured to the upright 341, for example by means of a rivet 360, and its horizontal leg has a shouldered stud 361 riveted thereto.

Journalled on the shouldered stud 361 is a lever 362 which is pivotally mounted on the shank 364, Figure 19, of a boss 365 on the plate 171. A nut 366 threadedly engages the shank 364 for retaining the lever 362 thereon.

A pin 367 is mounted fixedly in a lateral hole in the bar 342 and extends through an elongated clearance hole 368 in the plate member 355, and this pin forms a shaft upon which is mounted a lock member 370, Figure 24. The lock member has a straight body portion 371, the left end of which has a hole therein which is journaled on the pin or shaft 367. An arm 372 projects upwardly from the left end of this body portion. The other end of the body portion may have formed integral therewith a depending tongue or lug portion 373.

Intermediate the ends of the body portion is a projecting stud 374. A bracket 375 has a base portion 376 secured to the bottom plate 171, and an upright portion 377 having an angular camming surface 378 against which the stud 374 cams when the bar 342 moves under conditions to be presently described, it merely being sufficient to say at this point that; when the bar moves to the left, the stud moves down the incline of the camming surface and the body portion 371 assumes a horizontal position and the depending lug 373 engages a slot in a ratchet plate (to be presently described) and locks the rotor 172 against movement. When the bar 342 again moves to the right, the stud 374 moves up the incline of the camming surface, and the lock member 370 again assumes the position shown in Figure 24. The arm 372 and the upright 377 carry studs to which are connected the ends of a spring 379 which urges the lock member in a clockwise direction about the shaft 367.

Mounted on the interior of the wall portion 320 is a pair of aligned lugs 380 spaced apart vertically and having aligned holes therein for a retaining pin 381. Spaced apart circumferentially from the lugs 380 is a pair of lugs 382 also spaced apart vertically and in alignment with the lugs of the pair 380. The lugs 382 also have aligned holes therein to accommodate a retaining pin 383. An arcuate strip or web 384 contacts the inner surface of the wall portion 320 and is positioned between and is guided by said lugs (Figures 20 and 21). The web 384 has its left end extending into a slot formed in the boss 304 the inner face of which is flush with the inner face of the boss bounding the cavity 312. The web 384 carries a lug 385 with a hole therein to which one end of a link 386 is pivotally connected. The other end of the link extends through a hole near the end of the lever 362 and thereby operatively connects the lever and the web together. When the lever is in the position shown in Figure 20, the end 384a of the web 384 extends through the slot in the boss 304 and into the cavity 312. The outside face of the end 384a may bear the word

"Empty," and this is visible through the transparent plate 307 when in the position shown in Figure 20. In elevation this may be seen in Figures 14 and 16.

An arcuate plate 387 is rigidly secured on the plate 196, Figures 20, 21 and 22. The arcuate plate may be secured to the plate 196 by means of rivets 388, and extends into the open arcuate portion 266 formed in the bottom plate 177 of the rotor (see Figure 18) so that it can properly cooperate with the pawl tooth 352 on the pawl member 347 (see Figures 20, 21, and 25) and with the lock member 370 (see Figure 24). The plate 387 has a notch or slot 389 which the tongue or lug portion 373 of the lock member 370 engages each time an article is removed from the cavity 171 of the rotor, and which said lug disengages each time the next succeeding article enters the cavity 171 of the rotor. The plate 387 also has a series of ratchet teeth 390 formed thereon facing the pawl member 347, the pawl tooth 352 of which is positioned to traverse the ratchet teeth when an article is positioned in the cavity 171 of the rotor, due to the fact that the article (Figs. 20 and 21) engages the projecting end of the plunger 298, moves it endwise, and the head 299 acts against the arm 338 causing it to advance the upright 341 and the bar 342, so as to bring the pawl tooth into the range of the ratchet teeth 390. When an operator inserts the proper coins and turns the rotor in a clockwise direction as seen in Figure 21, the rotor cannot return, no matter where the rotor is stopped, until the removal of the article 149 from the rotor cavity 171 causes the pawl member to be withdrawn from engagement with the ratchet teeth 390 (due to disengagement of the plunger 298 by the article) permitting the pawl tooth, the bar 342 and the upright 341 to move, under the urge of the spring 358, to a point where the pawl tooth is out of the range of the ratchet. This movement also effects the advance of the "Empty" flag 384 into view in the transparent panel 307 when the rotor moves from position Figure 21, to position Figure 20, and at the same time the pin 374 (Figure 24) is moved down the incline 378 and the locking tongue 373 is lowered and engages the slot 389, thereby locking the rotor against movement.

If no succeeding article enters the cavity 171 (due to the shelf being empty, for example), the rotor remains locked and the flag 384 remains visible through the panel 307. On the other hand, if a succeeding article enters the cavity 171, the plunger 298 is pushed endwise, as above described, unlocking the rotor and withdrawing the flag 384 from the transparent panel 307, and the rotor is ready to vend the article when the proper coins are put in either one of the coin slots 39 or 41.

In order to adjust the machine to handle bottles or other round articles of different diameters, the arm 170 of the shelf advancing dog 221 (Figure 22) may have an elongated pad or boss 395, shown in dot-dash lines, and this boss may have, in addition to the tapped hole 396, shown as engaged by a shouldered screw 397, a tapped hole 398. To use smaller bottles or other round articles in the machine, the shouldered screw may be disengaged from the tapped hole 396 and screwed into the tapped hole 398, and the leverage (radial distance from the center of the screw to the center of the shaft 191) is reduced, so that when the rotor is operated, the movement of the article shelf 82 is correspondingly reduced—thus

the machine may be adjusted for more than one size of articles.

Referring now to Figures 7, 8, 20, and 21, spaced uprights 399 and 400, define a vertical opening in the front wall of the cabinet 30. Secured to the upright 399 and framing one edge of the opening is a breaker strip 401, and secured to the upright 400 and framing the opposite edge of the opening is a breaker strip 402. A dowel 403 is provided between the upright 399 and the breaker strip 401, and a similar dowel 404 is provided between the upright 400 and the breaker strip 402, suitable grooves being formed therein to accommodate the dowels. The face 405 of the breaker strip 401 adjacent the delivery rotor 172 is concave and is spaced apart slightly from the rotor. As insert strip 406 therein forms rubbing contact with the rotor and forms a thermal barrier to prevent cold air from falling out of the cabinet. The insert strip is preferably formed of rubber or the like.

Likewise the face 407 of the breaker strip 402 adjacent the rotor is concave and is spaced apart slightly from the rotor. An insert strip 408, preferably formed of rubber or the like, therein forms rubbing contact with the opposite side of the rotor.

An arcuate member 409, the cross-section of which is generally U shaped, has its internal channel 410 spanning the bottom plate 177 of one rotor, the plate 212 of the rotor, and the mechanism therebetween (as seen in Figures 14 and 23). The arcuate member has formed integral therewith on one end thereof a flat portion 411, and on the other end a flat portion 412. The portion 411 has a boss 413 which extends into a hole in the breaker strip 402 and is secured to the latter by means of a screw 415. The portion 412 likewise has a boss 414 which extends into a hole in the breaker strip 401 and is secured to the latter by means of a screw 416.

Referring to Figure 23, the stationary plate 212 carries a plurality of lugs 417 having countersunk holes 418 formed therein. These lugs fit in suitable sockets (not shown) in the breaker strips with the insert strips therebetween, four such lugs being provided on each plate, and they are secured to the breaker strips by means of flat head screws passing through the holes 418.

The cam 285 secured to the overhanging portion 283 of the rotor top plate 280 by means of rivets (Figures 17 and 18) constitutes a lock-out cam. The overhanging portion 283 and the cam 285 at the ends 283a and 285a respectively are beveled to form an entering wedge. Referring now to Figures 20 and 21, a vertical bar 419 is secured to the breaker strip 401 on the inside and adjacent to the concave face 405 thereof. This bar has a channel formed therein and fitting in the channel is a series of lockout members 420. Each lockout member may be equal to the length from the cam 283, 285 on one rotor to the cam on the next one above or below it. There are as many lockout members as there are rotors, and cooperating with either end one in the series is a similar extra lockout member which may or may not be equal to the length of a rotor. A horizontal barrier plate (not shown) may be provided at each end of the channel, and the distance between these barriers is equal to the sum of the lengths of all the lockout members, plus the thickness of the cam 283, 285, and plus a few thousandths of an inch clearance; so that when the cam enters between the adjacent ends of any two of said lockout members, the cams on all the other

rotors are locked out—making it impossible to operate more than one rotor at one time.

In Figure 29 is shown a view of a portion of the vertical bar 419. Positioned in the channel formed therein are shown the adjacent ends of two lockout members 420, meeting one another within a transverse clearance slot 421 through which a rotor cam can enter in the direction of the arrow. The ends of the lockout members are beveled at 422 which are first engaged by the beveled ends 283a, 285a of the cam and cammed parts so that the cam can enter between the abutting ends of said lockout members. Figure 30 is a view similar to (but 90 degrees displaced from the view, Figure 29, and showing the lockout members positioned in the channel in the bar 419.

It will be noted that the bottom fixed plate 212 (below the bottom rotor), is the only one carrying the double coin control locking arrangement (202, 204, 205, 206, 207, 208, etc.), as the single locking arrangement suffices for the entire machine.

To take care of instances where a change between the relation of the ratchet arm 121 with respect to the dog arm 170 is indicated, the link member 148, Figure 8, may be formed of two overlapping members 148a and 148b. Formed in the member 148b are spaced tapped holes engaged by bolts 423 from below. Formed in the member 148a are spaced elongated slots 424 through which the bolts 423 extend, the heads of the bolts being below the member 148a, and adapted to clamp both members together in any desired setting. The linkage is longest as shown in Figure 8 and with the bolts at the left ends of the slots, the linkage would be shortest. In order that air may circulate over and cool the bottles the shelves are provided with holes 425, Figure 2, and the stationary plates 100 also have holes 426 formed therein.

Operation

With the machine loaded and the contents refrigerated, the purchaser may insert the proper coin in either the coin slot 39 or the slot 42. If the coin is placed in slot 39 it releases the rod 208. The rod 207 remains locked because it is controlled by the mechanism associated with the coin slot 42; therefore, as the purchaser selects the rotor containing the flavor wanted, and rotates the same by grasping the knob 318 and moving it toward the left, the notch 200 in the dog 188 acts against the roller 201 so that the support for the roller fulcrums about the pin 205, and the pin 206 traverses the arcuate slot 215. The stud 186 is moved to the left as seen in Figure 22 by this manual operation of the rotor. This stud bears against the arm 187 and causes the arm to move therewith and thereby the dog 188 is moved in a clockwise direction. The lug 184 swings into engagement with the curved dent 216 formed in the dog. The rotation of the rotor tensions the spring 244 and the urge of this spring returns the rotor to its normal position after the purchaser removes the article from the rotor cavity.

As the rotor is turned in the manner above described the pawl 352 is in engagement with the teeth of the curved ratchet plate 387, and this ratchet prevents the rotor from returning to its normal position as long as the article remains in the cavity 171 in the delivery rotor. Due to the fact that the plunger 298 is in contact with the article, as soon as the operator removes the article from the cavity the plunger 298 is released and this in turn releases the lever 338 and the member 341. Releasing the pawl from engagement

with the ratchet causes the tongue 373 of the lock member 370 to descend and contact with the ratchet plate 387. With the release of the ratchet the rotor, under the urge of the spring in the base of the machine, returns to its normal position with the cavity positioned within the machine to receive the next article. As the rotor reaches its normal position the tongue 373 of the lock member, which has been sliding along on the surface of the ratchet plate 387, enters the slot 389, and thus the rotor is locked against movement at the same time the signal 384 is moved to a point where it is visible through the transparent panel 307 in the rotor.

The shelf 82, which contains the articles supplied to the rotor which has just been operated, is ratcheted forward (in a clockwise direction as viewed in Figure 11) by the ratchet arrangement under the urge of the spring 253 in the base, and the next succeeding article in the guide is thus advanced into the rotor cavity 171. The article displaces the plunger 298 thereby releasing the lock, withdrawing the signal 384 from the display cavity, and releases the pawl so that it may again engage the ratchet when the rotor is subsequently operated.

If all of the articles on the shelf have been exhausted no article can enter the cavity in the rotor and, therefore, the rotor remains locked and the signal in the display window indicates that that shelf in the machine is empty. If the purchaser, after placing the proper coins in the machine, finds that the flavor desired is exhausted and does not want any of the other flavors, he may press the coin-return button 40 or 43, depending on whether the coil is placed in the slot 39 or 42.

Although I have shown and described one embodiment by way of example to illustrate the invention, it is obvious that many changes in the arrangements herein shown and described may be made by those skilled in the art within the bounds of the appended claims:

I claim:

1. In a vending machine, a rotatable shelf, a stationary support above said shelf, said support having depending portions defining a path through which articles to be vended must pass, article delivery means at the outer end of said path to sequentially receive and deliver said articles, leverage members and ratchet means between said article delivery means and said shelf for moving said shelf after each article is delivered, and article pusher means movable on said shelf and adapted to follow up the article on the inner end of said path.

2. In a vending machine, a vertical shaft, a circular shelf freely rotatable thereon, guide means above said shelf and cooperating therewith to form a guideway for articles to be vended, article delivery means including an article cavity movable from a position, where it receives articles from said guideway, to a second position where a purchaser may remove an article therefrom; and means between said shelf and said delivery means for advancing said shelf only as said delivery means is returning from said second position to said first mentioned position.

3. In a vending machine, a vertical shaft, a circular shelf freely rotatable thereon, guide means above said shelf and cooperating therewith to form a guideway for articles to be vended, cylindrical article delivery means having a vertical axis, an article cavity formed in said delivery means; said delivery means being adapted to be

moved from a position, where it receives articles from said guideway, to a second position where a purchaser may remove an article therefrom; an arm pivoted on said shaft and adjacent to said shelf, ratchet means partly on said arm and partly on said shelf, and means connecting said arm to said delivery means, whereby said arm may be moved freely on said shaft as said delivery means is moved from said first position to said second position.

4. In a vending machine, a vertical shaft, a circular shelf rotatable thereon, guide means above said shelf and cooperating therewith to form a guideway for articles to be vended, a vertical cylindrical article delivery means having an article cavity formed therein, said cavity being normally positioned adjacent the outer end of said guideway, said delivery means being adapted to be rotated to a position where an article in said cavity may be removed therefrom, an arm pivoted on said shaft beneath said shelf, ratchet means partly on said arm and partly on said shelf adapted to advance the latter, and lever means and a connecting rod between said delivery means and said arm and adapted to move the latter in a non-shelf advancing direction as said delivery means is moved in a direction away from its normal position.

5. In a vending machine, a vertical shaft, a circular shelf rotatable thereon, guide means above said shelf and cooperating therewith to form a guideway for articles to be vended, a vertical cylindrical article delivery means having an article cavity formed therein, said cavity being normally positioned adjacent the outer end of said guideway, said delivery means being adapted to be rotated to a position where an article in said cavity may be removed therefrom, an arm pivoted on said shaft beneath said shelf, ratchet means partly on said arm and partly on said shelf adapted to advance the latter, a connecting rod between said delivery means and said arm and adapted to move the latter in a non-shelf advancing direction as said delivery means is moved in a direction away from its normal position, and power means for moving said arm in the opposite direction and advancing said shelf.

6. In a vending machine, a cabinet, means to support and guide articles along a predetermined path therein, a vertical rotor having an article cavity therein normally positioned adjacent to the end of said path within said cabinet, a vertical shaft for said rotor, said rotor being adapted to be manually rotated on its shaft to a position where said cavity and an article thereon is positioned external to the walls of the cabinet and said article may be removed therefrom, spring means in the base of said cabinet connected to said shaft adapted to be tensioned by said rotation of said rotor and adapted to effect the return of said rotor to its normal position.

7. In a vending machine, a cabinet, means to support and guide articles along a predetermined path therein, a vertical rotor having an article cavity therein normally positioned adjacent to the end of said path within said cabinet, a vertical shaft for said rotor, a second shaft within said first mentioned shaft, said rotor being adapted to be moved to a position where said cavity and an article therein is positioned external to said cabinet and said article may be removed therefrom, spring means in the base of said cabinet connected to said second shaft adapted to be tensioned by said last movement

of said rotor and adapted to effect the return of said rotor to its normal position, means to move said articles along said path in steps, means connecting said last means to said first shaft, and a second spring means in said base connected to said first shaft and also tensioned by the movement of said rotor from its normal position to effect the advancing of said articles at least one step as said rotor is returning to its normal position.

8. In a vending machine, a cabinet, a vertical delivery rotor having an article cavity normally positioned inside said cabinet, means in said cabinet to deliver articles into said cavity, said rotor being adapted to be rotated to position said cavity outside said cabinet where an article may be removed therefrom, means to move said rotor to return said cavity to its normal position, locking means in said rotor effective as said rotor returns to said normal position for locking said rotor against movement, and means engaged by the succeeding article entering said cavity for disengaging said locking means.

9. In a vending machine, a cabinet, a vertical cylindrical article delivery rotor carried on a vertical shaft in said cabinet, said rotor having an article cavity formed therein which is normally positioned inside said cabinet, means in said cabinet for supporting and advancing articles to said cavity, said rotor being adapted to be rotated to a point where said cavity is accessible from the outside of said cabinet, and locking means on said rotor effective when said cavity is in said normal position and empty and made ineffective when an article is advanced into said cavity.

10. In a vending machine, a cabinet, a vertical cylindrical article delivery rotor carried on a vertical shaft in said cabinet, said rotor having an article cavity formed therein and also having a window formed therein spaced apart angularly from said cavity, said cavity being normally positioned inside said cabinet and said window being normally positioned outside said cabinet, means in said cabinet to sequentially advance articles into said cavity when the same is in its normal position, said rotor being adapted to be rotated to a point where said cavity is accessible from outside said cabinet, and a visual indicator adapted to be brought into view in said window when an article is removed from said cavity and said rotor is returned to its normal position, and adapted to be withdrawn from view by a succeeding article entering said cavity.

11. In a vending machine, a cabinet, a vertical cylindrical article delivery rotor carried on a vertical shaft in said cabinet, said rotor having an article cavity formed therein and also having a display window formed therein angularly spaced apart from said cavity, said cavity being normally positioned inside said cabinet and said window being normally positioned outside said cabinet, means in said cabinet to sequentially advance articles into said cavity when the same is in its normal position, said rotor being adapted to be rotated to a point where said cavity is accessible from outside said cabinet, a visual indicator movably carried by said rotor, means urging said indicator toward a visible position in said window, and control means cooperating with said indicator and acting against said urging means when engaged by an article in said cavity for preventing said indicator from being visible in said window.

12. A vending machine according to claim 11, in which said means connected to said indicator includes a plunger which extends into said article cavity, said plunger being adapted to be engaged and moved by an article delivered into said cavity by said advancing means, and adapted to be released by the removal of the article from said cavity by a purchaser.

13. In a vending machine, a cabinet, a vertical article delivery rotor carried on a vertical shaft in said cabinet and having a portion of its cylindrical surface on the exterior of the cabinet, said rotor having an article cavity formed therein and normally positioned inside said cabinet, a stationary support adjacent to one end of said rotor, ratchet means carried on said support, pawl means carried on said rotor, means controlled by an article in said cavity for moving said pawl in cooperative relation to said ratchet means, means in said cabinet for supporting and advancing articles to said cavity, said rotor being adapted to be rotated to a point where an article in said cavity is accessible to an operator and said pawl and ratchet means normally preventing the rotor from moving towards its normal position until the operator removes the article from said cavity, thereby disassociating said pawl means from said ratchet means.

14. A vending machine according to claim 13, in which said means controlled by an article in said cavity includes a plunger extending into said cavity, pawl releasing means, and motion transmitting means between said pawl releasing means and said plunger, whereby an article entering said cavity engages and moves said plunger and in turn said pawl is moved into cooperative relation with said ratchet means and the removal of the article by a purchaser releases said plunger and consequently withdraws said pawl from said cooperative relation.

15. A vending machine according to claim 13, in which said rotor also includes a window which is outside said cabinet when said cavity is in its normal position, and a visual indicator carried by said rotor is also controlled by said means controlled by an article, said indicator being adapted to be withdrawn from said window when said pawl is moved into cooperative relation with said ratchet means and being adapted to be moved to a position where it is visible in said window

5 10 15 20 25 30 35 40 45 50 as said pawl is withdrawn from cooperative relation with said ratchet means.

16. A vending machine according to claim 9, in which said vertical shaft carries a dog, the hub of which is keyed to said shaft, a fixed support adjacent to the end of said rotor, a follow slot means formed in said support the edges of which form camming surfaces, a camming member on said rotor and movable therewith, said camming member including a portion adapted to engage and cooperate with said camming surfaces during the movement of said rotor and including a second portion adapted to engage said dog, and spring means connected to said shaft and tensioned by said movement for urging said rotor back toward its normal position.

17. In a vending machine, a rotatable shelf disposed on a horizontal plane therein to form a support for articles to be vended, a stationary guide above said shelf having depending portions defining a predetermined path for said articles, article delivery means at the outer end of said path to sequentially receive and deliver said articles, a radial slot formed in said shelf, an article pusher having a body portion above said shelf and extending into said path, a depending portion on said pusher extending through said slot and guided thereby, a second depending portion on said pusher spaced apart from said first depending portion and also extending into said radial slot, sleeve means on each of said depending portions engaging the edges of said slot, and roller means on said article pusher both above and below said shelf for minimizing friction between said pusher and said shelf.

JAMES E. STEWART.
